(73) Assignee: **Multipoint Radio Incorporated**, Roseville, CA (US)

(57) **CLAIM**

(**) Term: **14 Years**

The ornamental design for a microwave antenna electronics housing, as shown and described.

(21) Appl. No.: **29/138,726**

DESCRIPTION

(22) Filed: **Mar. 16, 2001**

FIG. 1 is a rear perspective view of a microwave antenna electronics housing showing our new invention;

(51) LOC (7) Cl. **14-03**

FIG. 2 is a front perspective view of the invention;

(52) U.S. Cl. **D14/230**

FIG. 3 is a top plan view of the invention, the bottom plan view being a mirror image;

(58) Field of Search D14/230-238;

FIG. 4 is a front elevation view of the invention;

343/720, 900, 713, 878, 905, 906, 715,
749, 752, 895, 714, 806, 802, 823, 805,
872, 705, 708, 741, 840, 882, 702, 873,
881

FIG. 5 is a right side view of the invention, the left side view

being a mirror image; and,

FIG. 6 is a rear elevation view of the invention.

The broken lines in FIG. 5 are for purposes of illustration

only and form no part of the claimed design.
